COMBINED SEWING MACHINE SHIPPING CRATE AND STAND

John W. Krein, Westport, Conn., and Henry J. Milan, Clark, and William G. Hauser, Fanwood, N.J., assignors to The Singer Company, New York, N.Y., a corporation of New Jersey

Filed Sept. 23, 1965, Ser. No. 495,012

1 Claim. (Cl. 217—12)

This application is a continuation-in-part of our United States patent application Serial No. 351,954, filed March 16, 1964, now abandoned.

This invention relates to sewing machines and more particularly to the provision of a sewing machine shipping crate which after it has been used as a shipping crate can be dismantled and reassembled to form a sewing machine stand, and one of the primary objects of the present invention is to provide an improved item of this character.

Another object of the present invention is to provide an improved combined shipping crate and stand which is especially adapted to accommodate a treadle driven sewing machine.

A further object of the present invention is to provide an inexpensive improved method and means for shipping and mounting a sewing machine.

A still further object of the present invention is to provide an improved sewing machine shipping crate assembly from the parts of which a sewing machine stand can be assembled.

Another object of the invention is to provide an improved combined sewing machine shipping crate assembly and stand assembly having panels that can be reversed so that when these panels form part of the shipping crate, their unfinished surfaces are exposed and when these same panels form part of the stand, their finished surfaces are exposed.

A further object of the invention is to provide an improved method and means for packing a treadle type sewing machine.

A still further object of the invention is to provide a combined shipping crate and stand having panels which form a portion of both the crate and the stand and which panels when assembled with other parts, form a complete shipping crate and which panels when assembled with still other parts, form a complete sewing machine stand.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

FIG. 1 is a front perspective view showing a sewing machine shipping crate embodying the present invention.

FIG. 2 is a front perspective view showing a sewing machine stand embodying the present invention, parts of the stand originally forming portions of the shipping crate shown in FIG. 1.

FIG. 3 is a top plan view of the shipping crate of FIG. 1 with the cover removed, and showing parts stored therein.

FIG. 4 is a cross sectional view of the shipping crate taken substantially on the plane 4—4 of FIG. 3, and

FIG. 5 is an exploded perspective view showing various parts of the sewing machine stand illustrated in FIG. 2.

As best seen in FIGS. 1 through 5, the improved combined sewing machine shipping crate 15 and stand 16

2

comprises a table top 17 having a conventional sewing machine receiving opening 18 and two band receiving holes 19—19. The table top 17 has a finished side 21 and an unfinished side 22.

5 The combined crate and stand 15—16 also comprises a left end panel 23 having a finished side 24 and an unfinished side 26, and a right end panel 27 having a finished side 28 and an unfinished side 29. The crate and stand 15—16 also comprises a back panel 31 having a finished side 32 and an unfinished side 33, and a front panel 34 having a finished side 36 and an unfinished side 37. The table top 17 and all of the panels 23, 27, 31 and 34 have holes 38 for receiving various sized screws 41 and bolts 42. A treadle 44 has a finished side 46 and an unfinished side 47 and a left leg support 48 has a finished side 49 and an unfinished side 51, whereas the right leg support 52 has a finished side 53 and an unfinished side 54.

Many of the hereinbefore numbered items, namely the 20 table top 17, the panels 23, 27, 31 and 34, the treadle 44 and the leg supports 48—52 serve two functions. When their first or unfinished sides are exposed and assembled as shown in FIG. 1, they form part of the shipping crate 15 and when their second or finished sides are exposed, they form part of the stand 16 shown in FIG. 2. In addition, there are many items which form part of the shipping crate 15 but which are not needed when the stand 16 is assembled, and these parts may be discarded. Specifically, the shipping crate 15 has the following parts 30 which do not form part of the stand 16: the eight batten strips 66, 67, 68, 69, 71, 72, 73, and 74, which are positioned to strengthen the crate 15, the insert 76 which during shipment of the crate 15 closes the hereinbefore mentioned opening 18, a bottom portion 77 of the shipping crate 15, a front portion 78 of the shipping crate 15, and a number (FIG. 3) of internal bracing members 81, 82, 83, 84, 85, 86, 87, 88, 89, 90 and 91. It should be noted that the batten strips 69 and 74 are wide enough to overlap the ends of the opening 18 and thus hold the 40 insert 76 in place during shipment. Many of the edges and corners of these bracing members are padded with felt as indicated by the numeral 92. In addition, the finished sides 21, 24, 28, 32, 36 and 46 of the parts 17, 23, 27, 31, 34 and 44 are covered with protecting sheets of 45 corrugated cardboard 93, 94, 96, 97, 98 and 99. Also the cardboards 94 and 96 are covered respectively with protective sheets of plywood 101 and 102.

The shipping crate 15 is designed to house a sewing machine 104, a left leg 106, a right leg 107, a treadle support bar 108, two treadle positioning collars 109, a pair of treadle mounting clamps 110, a pitman rod stud bracket 111, two pitman rod studs 112, a pitman rod 113 complete with two rod connections 114, a pair of machine rest blocks 115, a band wheel 116, a belt or driving band 120, a band wheel shaft 122, and a plurality of the nuts, bolts, and screws, etc., housed in a bag 124. The right and left legs 107 and 106 are substantially U-shaped in that each 50 comprises a vertical front portion 117, a horizontal bottom portion 118, and a forwardly offset rear portion 119, the bottom portions 118 being provided with cutouts 123. The legs 106 and 107 and the treadle support bar 108 are apertured at appropriate locations to accommodate the various bolts and screws used to fasten the various parts together 55 to form the machine stand 16. The right leg 107 is equipped with a band wheel shaft support bracket 126 and a band wheel shaft locking bracket 127. The items 126 and 127 are fully described and claimed in co-pending patent application Serial No. 351,955, filed March 16, 1964, in the name of H. J. Milan.

60 It will be understood that the shipping crate 15 is fully assembled and packed in the factory and that, when the packed crate 15 arrives at the store or home where the

stand 16 is to be assembled, the crate 15 will be placed in the position shown in FIG. 1 with the arrows 128 pointing upwardly. Then all of the screws which hold the batten strips 69 and 74, the table top 17 and the left leg support 48 are removed. These screws are retained and will be used when the stand 16 is assembled. Then all contents (FIG. 3) of the crate 15 are removed and the empty crate is turned upside down and all remaining screws removed. Next the following parts of the crate 15 are set aside: the table top 17, the left end panel 23, the right end panel 27, the back panel 31, the front panel 34, the treadle 44, the left leg support 48 and the right leg support 52. All of the other wooden parts of the crate 15 are discarded.

The stand 16 is assembled in the following manner. The two end panels 23 and 27, with their finished sides 24 and 28 exposed, are secured to the front and back panels 34 and 31 with their finished sides 36 and 32 exposed by means of a plurality of wood screws. Next the table top 17 with its finished side 21 uppermost is secured to the panels 23, 27, 34 and 31. Thereafter the assembly is turned upside down and the machine rest blocks 115 are secured to the lower surface of the table top 17 with portions of these blocks 115 extending in the opening 18. Then the right leg 107, which carries the band wheel shaft support bracket 126 and the locking bracket 127, is secured to the unfinished surface 29 of the right end panel 27. In like manner the left leg 106 is secured to the unfinished surface 26 of the left end panel 23. Then the treadle 44 with its finished side 46 uppermost is mounted on the treadle support bar 108 by use of the mounting clamps 110 and the positioning collars 109. Then one of the pitman rod connectors 114 is connected to the treadle 44 by means of one of the pitman rod studs 112 and the bracket 111, and the band wheel shaft 122 is passed through the hub of the band wheel 116 and through the holes in the brackets 127 and 126. Next, the two leg supports 48 and 52 are placed on the bottom members 118 of the legs 106 and 107, and the treadle support bar 108 is placed in the cutouts 123—123 of the bottom portions 118 after which bolts are used to secure the supports 48 and 52 and the treadle support bar 108 to the legs 106 and 107. Then the other pitman rod stud 112 is passed through the upper pitman rod connector and the treadle 44 is drivingly connected to the band wheel 116, after which the treadle 44, the pitman rod 113 and the band wheel 116 are properly aligned and all connections tightened. Then the stand 16 is turned over and the sewing machine 104 placed into the opening 18 and a driving band 120 connected between the band wheel 116 and the sewing machine 104.

The following are some of the advantages of our new combination shipping crate and stand 15—16.

(A) It is inexpensive to manufacture because many of the parts which form the shipping crate 15 are reused to form the sewing machine stand 16. Also some of the wood screws which hold the crate 15 together are used as part of the stand 16.

(B) The shipping weight is reduced because if parts of the crate 15 were not reused, the crate 15 would have to be enlarged to accommodate not only the sewing machine 104, support legs 106—107, etc., but also a complete stand.

(C) Because the finished sides of the parts of the sewing machine stand 16 are placed inwardly in the crate 15 and protected by corrugated cardboard 94—96—97—98—99, these sides will present a good appearance when used as part of the sewing machine stand 16.

(D) By securing the right and left leg supports 48 and 52 to the bottom of the legs 106 and 107, the length of the legs, per se, are reduced and thus the size of the crate 15 which houses these legs is reduced.

(E) All necessary holes are drilled in the factory and thus it is easy for anyone to convert the shipping crate 15 into the stand 16.

Having thus described the invention, what we claim herein is:

A combined sewing machine shipping crate assembly and stand assembly comprising a plurality of members some of which have unfinished and finished sides and certain of which when assembled in one manner form a crate for shipping a sewing machine and which when assembled in another manner form a stand for supporting a sewing machine, said members comprising:

- (a) a sewing machine which when forming part of said crate assembly is housed in said crate and which when forming part of said stand assembly is supported on said stand;
- (b) an apertured top member which when forming part of said shipping crate assembly has its unfinished side outermost and which when so used acts as the cover for said crate, and when forming part of said stand assembly has its finished side outermost, and which when so used acts as the tabletop for supporting said sewing machine on said stand;
- (c) a closure member which when forming part of said shipping crate assembly closes the aperture in said top member;
- (d) a back member which when forming part of said shipping crate assembly has its unfinished side outermost and which when so used acts as a side panel for said crate and when forming part of said stand assembly has its finished side outermost and which when so used has its upper edge secured to the rear edge of said top member;
- (e) a pair of end panel members which when forming parts of said shipping crate assembly have their unfinished sides outermost and which when so used act as ends for said crate and when forming parts of said stand assembly have their unfinished sides outermost and which when so used have their upper edges secured to opposite edges of said top member, and their back edges secured to opposite ends of said back member;
- (f) a pair of substantially U-shaped leg members each having upper and lower ends, said lower ends being formed with horizontal bottom portions, said leg members which when forming part of said crate assembly are housed in said crate and which when forming part of said stand assembly have their upper ends secured to the unfinished surfaces of said end panel members;
- (g) a front panel having a vertical height less than the vertical height of said back panel and when forming part of said stand assembly has its finished side outermost and which when so used has its upper edge secured to the front edge of said top member and its opposite ends secured to the front edges of said end panel members;
- (h) a pair of leg support members which when forming part of said shipping crate assembly act as batten strips therefor and which when used as part of said stand assembly are secured to the lower horizontal bottom portions of said leg members and act as leg supports therefor; and
- (i) a plurality of miscellaneous parts which when forming part of said shipping crate assembly close the front and the bottom of said shipping crate.
